UNITED STATES PATENT OFFICE

108,099

DESIGN FOR A LONGITUDINAL ARCH SUPPORT

Ross H. Johnson, Indianapolis, Ind.

Application January 9, 1937, Serial No. 66,983

Term of patent 14 years

To all whom it may concern:

Be it known that I, Ross H. Johnson, a citizen of the United States, residing at Indianapolis, county of Marion, and State of Indiana, have invented a new, original, and ornamental Design for a Longitudinal Arch Support, of which the following is a specification, reference being had to the accompanying drawing forming part thereof:

The design features which comprise my complete design include the substantially oval portion of increased thickness which is situated near the upturned side edge of the support, the major axis of the same extending approximately longitudinally of the support; and in the arrangement of marking lines, substantially as illustrated.

I claim:

The ornamental design for a longitudinal arch support, as shown and described.

ROSS H. JOHNSON.
